UNITED STATES PATENT OFFICE.

JERRY R. RYAN, OF ST. PAUL, MINNESOTA, ASSIGNOR, BY MESNE ASSIGNMENTS, TO
KE HAW KE MANUFACTURING COMPANY, OF MINNEAPOLIS, MINNESOTA.

TUBE-VULCANIZING DEVICE.

Application filed October 18, 1924. Serial No. 743,928.

To all whom it may concern:

Be it known that I, JERRY R. RYAN, a citizen of the United States, residing at St. Paul, in the county of Ramsey and State of Minnesota, have invented certain new and useful Improvements in Tube-Vulcanizing Devices; and I do hereby declare the following to be a full, clear, and exact description of the invention, such as will enable others 10 skilled in the art to which it appertains to make and use the same.

My invention relates to a vulcanizing device intended for general use but especially adapted for use in vulcanizing the bases of 15 straight or bent valve stems to the inner tubes of pneumatic tires, and is in the nature of an improvement on the vulcanizing device shown in the patent of William Oppenheimer 1,323,544 of date December 2, 1919. 20 To the above end, generally stated, the invention consists of the novel devices and combinations of devices hereinafter described and defined in the claims.

In the accompanying drawings, which 25 illustrate the invention, like characters indicate like parts throughout the several views.

Referring to the drawings:

Fig. 1 is a perspective view of the improved vulcanizing device;

30 Fig. 2 is a longitudinal central section, on an enlarged scale, and illustrating an inner tube held on the device during the vulcanizing process to secure a valve base thereto; and

35 Fig. 3 is a transverse vertical section taken on the line 2—2 of Fig. 1.

The numeral 4 indicates a hollow body 40 preferably formed of cast metal and the interior thereof affords a heating or steam chamber 5 adapted to receive steam as a heating agent. Steam is admitted to the heating chamber 5 through a steam pipe 6, leading from any suitable source of supply, not shown. This steam pipe 6 is tapped 45 into a boss on the back of the body 4 at the center thereof and affords a support for the vulcanizing device. Attached to the bottom of the body 4, close to one end thereof, is a normally closed valve 7 which leads from

50 the steam chamber 5 and through which condensed steam may be drawn off, or said valve may also be used to facilitate a free flow of steam in the steam chamber 5.

This body 4, as shown, is rectangular in 55 horizontal cross section, and the bottom

thereof is rounded transversely from the front to the rear. The top of the body 4 is flat and affords a work-supporting surface 8 for articles to be vulcanized such as inner tube 9, as shown in Figs. 2 and 3. Articles to be vulcanized are held pressed on the work-supporting surface 8 by a clamping device while being treated by the heat of the steam conducted through said work-supporting surface. This clamping device includes 60 a flat plate 10 which is held in its proper position upon the inner tube 9 under the required or desired pressure by a hand screw 11 having screw-threaded engagement with the free end of a U-shaped arm 12 which 65 overlies the work-supporting surface 8.

The arm 12 at its lower end is hinged at 70 13 to and between a pair of depending hinge lugs 14 cast integral with the bottom of the body 4 for vertical swinging movement. 75 This arm 12 extends upward transversely over the body 4 at the front thereof and when not in use hangs down under said body so that the same is entirely out of the way and does not interfere with the operator. The lower end of the hand screw 11 is pointed and seated in a cup-shaped seat 80 15 formed in the top of the clamping plate 10 at the center thereof. This engagement of the hand screw 11 with the plate 10 permits said plate to freely adjust itself onto the inner tube 9 so that it will press equally thereon at all points and it also materially facilitates the free turning movement of the hand screw 11 on the plate 10.

Preferably, as shown in Figs. 2 and 3, a bag containing powdered soap stone, or other suitable material, is interposed between the inner tube 9 and clamping plate 10, especially when vulcanizing a valve base to an inner 90 tube, to compensate for the varying thickness in the inner tube and securely press the same at all points onto the work-supporting surface 8.

To provide means for receiving a straight 100 valve stem or a bent or crooked valve stem either of the angle or double bent type and thus permit an inner tube and its valve base to be placed on the work-supporting surface 8 for vulcanization without distorting, injuring or otherwise affecting the fabric thereof or the valve stem, there is formed in the top of the body 4 a valve stem passageway 17 which leads to a valve stem chamber 18. This valve stem chamber 110

18 is centrally located within the steam chamber 5 and is separated therefrom by a wall 19 which extends from the top to the bottom of the body 4 and is cast integral therewith. Said valve stem chamber 18 is relatively narrow from the front to the rear of the vulcanizing device but relatively long longitudinally thereof and extends laterally from the valve stem passageway 17. The 10 width of the valve stem chamber 18 is slightly greater than that of the largest valve stem used in connection with such inner tubes and the length thereof is such as to freely receive a bent valve stem either of the 15 angle or double bent type. This formation of the valve stem chamber 18 is of the utmost importance and by reference to Fig. 2, it will be noted that the size of the valve stem passageway 17 and the valve stem chamber 20 18 is such as to freely receive a straight valve stem 19, as indicated by broken lines in Fig. 2, or a bent valve stem 20, as indicated by full lines in Fig. 2.

To insure a snug fit of a valve stem in the 25 passageway 17 and properly centralize the same therein, there is provided interchangeably usable bushings or rings 21 of the same external diameter and adapted to be removably mounted in a recessed seat 22 in the 30 mouth of the passageway 17 at the work-supporting surface 8. The axial openings in these bushings vary in size to fit different sized valve stems.

When a valve stem base is to be vulcanized 35 to an inner tube or the inner tube vulcanized in the immediate vicinity of its valve stem one of the bushings 21 of the proper size is telescoped onto the valve stem and said valve stem inserted through the passageway 17 and into the valve stem chamber 18. At the 40 completion of this movement of the valve stem, the respective bushing 21 will enter the seat 22 and automatically center the valve stem in the passageway 17 and at the same time form a tight joint between said 45 valve stem and the work-supporting surface 8. With the valve stem thus positioned, the respective portion of the inner tube and the valve base will lie flat upon the work-supporting surface 8 without distorting the 50 tube or valve stem base. The bag 16 is then placed on the inner tube and the plate 10 on said bag. The arm 12 is then swung upward to position the hand screw 11 over the 55 seat 15 and said hand screw is adjusted to engage the plate 10 and press the same onto the bag 16 which in turn presses the inner tube and valve base onto the work-supporting surface 8 under the desired pressure. 60 Steam is then introduced into the steam chamber 5 and the heat conducted through

work-supporting surface 8 will act on the parts to be vulcanized, as is well understood.

In the bottom of the body 4, leading from the valve stem chamber 18, is a hole 23 65 axially aligned with the valve stem passageway 17 and located between the hinged lugs 14 for the escape of dirt or other foreign matter or to receive an unusually long valve stem. 70

What I claim is:

1. A vulcanizer comprising a body member having a heating chamber, a valve stem chamber, a work-supporting surface, and a valve stem passageway leading from said 75 work-supporting surface to the valve stem chamber, said valve stem chamber being extended laterally from the projected axes of said passageways to afford clearance for a bent valve stem inserted through said passageway. 80

2. A vulcanizer comprising a body member having a heating chamber, a valve stem chamber, a work-supporting surface, a valve stem passageway leading from said work- 85 supporting surface to the valve stem chamber, a clamping arm hinged to said body for transverse swinging movement over the top of the work-supporting surface, a clamping screw mounted on the free end of the arm, 90 and a clamping plate adapted to be interposed between the clamping screw and work-supporting surface, said valve stem chamber being extended from said passageway transversely of the swinging movement of the 95 clamp arm to afford clearance for a bent valve stem inserted through said passageway.

3. A vulcanizer comprising a rectangular body member that is U-shaped in cross section and having a heating chamber, a centrally located valve stem chamber extending from the top to the bottom of said body and surrounded by the heating chamber, the top of said body affording a work-supporting surface, and a passageway leading from the work-supporting surface to the valve stem chamber, said valve stem chamber being extended longitudinally from the projected axis of said passageway to afford 100 clearance for a bent valve stem inserted through said passageway, said passageway being relatively narrow transversely of said body. 105

4. The structure defined in claim 1 in 110 which the valve stem passageway is provided with an expanded portion to afford a seat and in further combination with interchangeably usable washers removably mounted in said seat. 115

In testimony whereof I affix my signature.

JERRY R. RYAN.
